CLAIM

The ornamental design for a pallet stabilizer, as shown and described.

DESCRIPTION

FIG. 1 is a perspective view of a pallet stabilizer taken from the bottom, back and right side thereof;

FIG. 2 is a perspective view similar to FIG. 1, but wherein the pallet stabilizer includes cut away lines to clearly show disclaimed portions of the pallet stabilizer that are folded inwardly;

FIG. 3 is a bottom plan view thereof;

FIG. 4 is a top plan view thereof;

FIG. 5 is a back elevation view thereof;

FIG. 6 is a front elevation view thereof;

FIG. 7 is a right side elevation view thereof; and,

FIG. 8 is a left side elevation view thereof.

The broken lines in the drawings illustrate portions of the pallet stabilizer that form no part of the claimed design. The
